HEADLESS NAIL

Charles M. Lindstrom, Westerly, R. I., assignor to Bostitch, Inc., Stonington, Conn., a corporation of Rhode Island

Application December 16, 1952, Serial No. 326,234

2 Claims. (Cl. 85—10)

This invention relates to fastener devices for attaching various objects and articles and more particularly to a preformed bridgeless staple of inverted V-shape having divergent legs adapted to be bent into parallel, contiguous relationship before driving to provide a headless brad, tack or nail.

One object of the invention is to provide a preformed headless staple having divergent legs connected at the top by relatively short sections extending in parallel contiguous relationship above their divergent portions so that said legs may be forced together in alinement with their upper parallel portions to provide a headless brad, tack or nail.

Another object is to provide a headless brad, tack or nail formed from a length of wire bent intermediate its ends into a narrow loop with the sides of the loop in contiguous, parallel relationship and continued downward in a pair of legs spread apart in divergent relationship and adapted to be forced together in alinement with the sides of the loop before driving the brad into the work.

Another object is to provide a preformed staple having divergent legs and so constructed and arranged that it may be finally formed into a headless brad in a stapling or tacking machine with the opposite legs in contact throughout their length below the looped connecting portion without causing spreading of the legs at their point of joinder.

Another object is to provide a method of preforming a wire staple by bending or doubling a length of wire on itself intermediate its ends in the form of a closed loop having parallel contiguous side portions and then bending the main portion of the legs below the loop into divergent relationship so that finally they may be brought together in alinement with the sides of the loop to form a headless brad, tack or nail.

Another object is to provide a preformed staple of inverted V-shape which may be finally shaped with its opposite legs closely connected together at the top without a crown or crossbar and extending throughout their length in parallel contiguous relationship.

Another object is to provide a headless brad, tack or nail for use in fastening laminations of wood or other strips and adapted to be countersunk in the material in which it is driven without marring the exposed surface thereof.

The following specification describes the invention as embodied in a preformed staple with a preferred method of constructing the staple from wire or thin strips of metal and finally shaping it as a headless brad, tack or nail prior to driving it into the work. The invention is illustrated by the accompanying drawing in which:

Fig. 1 is a perspective view of a portion of a strip or "stick" of connected staples constructed in accordance with the invention;

Fig. 2 is an enlarged end view of a staple of inverted V-shape, constructed in accordance with the invention and illustrating in dash-lines the manner in which it is finally formed with its legs in parallel contiguous relationship throughout their full length;

2

Fig. 3 is an end view of the staple strip or refill illustrated in Fig. 1 showing it as mounted on a tapered core or support shown in section as shaped to the configuration of the staples in the strip;

Fig. 4 is a sectional view of several layers of material shown as fastened together by the present improved headless brad formed from a staple of the present type;

Fig. 5 is a part-sectional end view of the operating 10 parts of a stapling implement which may be used for closing together the legs of the staple before driving it into the work;

Fig. 6 is a similar view showing the staple-bending means as having been operated to straighten and close 15 together the legs of the staple; and

Fig. 7 is a similar view showing the headless brad or nail formed from the staple as being driven into the work.

It has previously been proposed to provide a wire 20 staple having divergent legs connected at the top by an arcuate looped portion of the wire. When staples of such shape finally have their legs bent into parallelism the legs are spaced apart a distance twice the length of the radius of the arcuate connecting portion of the 25 wire at the top so that there will be a considerable opening or space between the parallel legs. In other words, when the legs of such staple are finally bent into parallel relationship they will be spaced apart by the connecting crown-portions and therefore cannot be used as 30 headless brads, tacks or nails. It is a principal object of the present invention to so preform the staple at the joinder of its legs that eventually the legs can be bent or straightened to lie in parallel contiguous relationship 35 throughout their length. With the present improved preformed staple the legs can be brought together into parallel contiguous relationship without a space therebetween and with no lateral projecting portions at the top, that is, it is rendered bridgeless in the form of a headless brad or nail.

40 Referring first to Fig. 1, the present improved preformed staple 2 may be constructed of wire or thin strip material by first bending or folding the wire or strip at a point between its ends, preferably midway therebetween, so as to provide a pair of divergent legs 3 of equal length. Usually, the ends of the legs are beveled 45 to sharpen their terminal points for ease in driving. During, or subsequent to, the first bending operation the wire in the sides 4 of the loop is pressed or swaged together to close the loop; that is, force its sides into 50 close abutting relationship for a relatively short distance indicated by the line *a* in Fig. 1. The length of the upper closely abutting portions 4 of the staple legs is shown in the drawing as approximately one-sixth of the full length of the staple, but these proportions may 55 be varied as desired, for example, by either shortening or lengthening the diverging portions 3 of the legs.

The preforming of the staples may be accomplished in suitable dies or swaging tools, either operating on the staples individually or when joined together in a strip or "stick," the form in which the staples are usually 60 packaged as a supply or refill for stapling implements. For example, the staples may be constructed initially with their legs diverging throughout the full length and subsequently the single staples or the staple strips may be 65 swaged along their upper portions to compress a relatively short length of the legs into parallel contiguous relationship.

The staples may be supplied to a stapling implement by straddling the strip or stick across a core or support 5, shown in Fig. 5, which extends longitudinally of the magazine of such a type of implement embodying means for feeding the whole strip forwardly to advance the fore-

most staple into position to be driven. Means for finally bending together the divergent legs 3 of the staple are illustrated in Figs. 5 to 7, being substantially the same as disclosed in my prior application for United States Letters Patent for Fastener-Applying Implement, Patent No. 2,714,207, dated August 2, 1955. In the invention of this patent the head of the implement is provided in its base with a relatively narrow throat 10 opening through the top just below the staple-supporting core 5. The opening 11 at the top of the throat or passage 10 is preferably beveled slightly on the sides to provide an easy entrance for the staple as it is driven down into the throat. The fastener-applying implement is provided with a reciprocable staple-driver 12 of the plunger-type having its lower portion formed into a thin blade 13 dimensioned to adapt it to slide through the throat 10.

The above-described implement is provided with bender-levers 15, so called, pivoted on studs 16 and mounting pins 17 at the top which form journals for a pair of rollers 18 engaging in cam-grooves 20 in a block-like member 21. The member 21 is attached to, or formed as a part of, a slideable sleeve 22 adapted to be reciprocated vertically of the implement, this part of the mechanism being illustrated and described more fully in my prior application identified above.

When the sleeve 22 is slid downwardly on the head of the stapling implement the block-like member 21 descends with it to cause the rollers 18 on the studs 16 to ride upwardly in the cam-groove 20. The cam-grooves 20 are of substantially L-shape, as indicated by dotted lines in Figs. 5 to 7, so that as the rollers 18 travel upwardly therein the upper arms of the levers 15 are forced apart to move their lower arms together as shown in Fig. 6.

This rocking motion of the levers 15 causes their lower arms to impinge against the divergent legs 3 of each staple after it is fed off from the forward end of the core 5, thereby forcing the legs of the staple together into parallel abutting relationship. After the above-described operation of the bender-levers 15 for closing together the legs of the staple, the driver 12 descends with its blade 13 passing between the opposing faces of the levers to drive the staple downwardly through the throat 10 and outwardly therefrom for inserting it into the work W. As shown in Fig. 4, the work W may consist of a board or backing B overlaid with a plurality of laminations b, or the work may be of any other nature in which parts are to be held together by headless brads, tacks or nails.

The present improved staple in its final form is particularly adapted for use as a brad for fastening together the parts of furniture, such as the front and sides of a drawer for a desk or table, and for many other uses where several layers of wood or the like are to be held together; the brad or nail being headless to adapt it to be countersunk and provide a practically invisible fastening.

After the headless brad or nail formed from the present improved staple has been driven into the work the driver-blade 13 is withdrawn and the cam-block 21 raised whereby the rollers 18 on the studs 17 are caused to travel down the inclined portions of the cam-grooves 20 to draw the upper arms of the levers 15 together and open their lower arms as shown in Fig. 5. The stapling implement then may be operated again to drive the next staple fed off from the end of the core 5.

It will be observed from the foregoing specification that the present invention provides a novel and improved preformed staple which is adapted to be eventually shaped as a headless brad, tack or nail; the present preforming operation insuring that when the divergent legs of the staple are bent toward each other they will be brought into contact and remain contiguous for driving it into the work. The upper portions of the legs of the staple where connected at the top will also lie in contiguous abutting relationship without projecting laterally to form an

obstruction or head when the brad is countersunk in the work.

The present method of forming the closed looped portions of the staple legs also has an important advantage in that when the legs are finally brought together by a bending operation they will have less tendency to spring apart due to the nature of the material, such as the tempered wire from which they are constructed. Stated another way, the legs of the staple will remain closed together in abutting relationship both while the staple is driven and after it has been applied to the work; and due to the fact that it has no projections at the top, that is being headless, it will not abrade, split or otherwise injure materials through which it is driven when the brad is countersunk beneath the upper surface of the work. As another advantage, the parallel legs being in full contact act to stiffen and reinforce each other to prevent them from bending or buckling. It is believed that the present invention embodies a novel and original method of preforming a staple with divergent legs in such manner that the legs may be brought together in parallel abutting relationship throughout their full length and caused to remain in this form during application of the finished brad, tack or nail in the work.

While the present specification and drawing illustrate the present improved staple as of conventional dimensions with a preferred proportion of the length of its preformed upper portion to the full length of the legs, these dimensions are subject to variation in accordance with requirements in use. Likewise, the thickness or width of the stock from which the staple is constructed may be varied at will and other modifications made within the purview of the present invention. Therefore, without limiting myself in this respect, I claim:

1. An improved staple having opposite legs of substantially uniform cross-section joined together at the top in a closed loop with the sides of said loop in contiguous abutting relationship throughout a relatively short portion of the length of the legs and extending in parallelism with median vertical plane, the remaining relatively long portions of the legs being of equal length diverging at an angle to each other, said loop at all times being within the lateral width of said legs whereby a headless brad is formed, the terminal end of each leg of the staple being beveled on opposite sides to provide a central sharpened point for penetration into the work whereby to cause the legs to retain their close abutting relationship without spreading apart as the staple is driven in the form of a headless brad.
2. An improved staple having opposite legs of substantially uniform cross-section joined together at the top in a closed loop with the sides of said loop in contiguous abutting relationship throughout relatively short portions of the length of the legs and extending in parallelism with a median vertical plane, the remaining relatively long portions of the legs being of equal length diverging at an angle to each other, said loop at all times being within the lateral width of said legs whereby a headless brad is formed, and the terminal end of each leg being beveled at least on the outside to provide a sharp point whereby to cause the legs to retain their close abutting relationship without spreading apart as the staple is driven in the form of a headless brad.
